RAZOR STROP CONTAINER AND SUPPORT-
ING DEVICEJohn E. Gillespie, Washington, D. C., assignor of
one-half to Sherman C. Shelton, Washington,
D. C.

Application August 22, 1939, Serial No. 291,403

8 Claims. (Cl. 51—201)

This invention relates to improvements in razor strop container and supporting devices from which the strop may be withdrawn for the purpose of sharpening razor blades and upon release thereof will automatically be returned within the container. The invention relates more particularly to improved razor strop container and supporting devices which serve to support and maintain the razor strop in operative position and to protect and disinfect the razor strop when it is in an inoperative position within the container.

In order to maintain razor strops in pliable condition for sharpening razors it is conventional to apply oil or other treating substances to the surface of the strop. Dust and other foreign particles accumulate on the strop surface and are forced into the fibers of the strop by the action of the razor as it is passed over the strop's surface. As a result the stropping surface is transformed into a breeding medium for bacteria, which are transferred from the hands of the operator, towels, or other objects which come into contact with the unprotected strop. During the sharpening operation, the bacteria are transferred to the razor which results in skin infections particularly when the skin is cut or otherwise broken during the shaving period. Heretofore protecting and disinfecting devices have been suggested although these devices have been ineffectual in completely disinfecting the strop while maintaining it in a protected covering from which the strop may be easily withdrawn and supported in an operative position. No means have been provided in the prior art devices to insure that the gaseous disinfecting substance will at all times and completely permeate the atmosphere within which the strop is confined. In order to remedy these and other deficiencies of the prior art, the improved razor strop container and supporting device is provided with a circulating system by virtue of which gaseous disinfecting substances are transferred to all parts of the interior of the container.

The circulatory system of the improved razor strop container and supporting device is provided by a plurality of apertured ducts positioned adjacent the edges of the strop. Air and gaseous disinfecting substances are forced through the ducts by the action of a plunger which is operated during the movement of the strop in and out of the container. The forced flow of the gas not only serves as means to cause distribution of the gas but also to insure vaporization of the disinfecting substances. In the

present embodiment of the invention, the ducts also serve as guide members for the plunger. In addition to causing the flow of gas, the plunger also serves as a counterweight to insure the return of the strop into the container after it has been released from its operative position.

In addition to the above defined objectives, the razor strop container and supporting device is provided with improved releasable means for maintaining the strop in operative position. The improved razor strop container is also formed substantially air-tight in order to eliminate the leakage of the disinfecting gas when the strop is withdrawn from and returned into the container.

The features of the improved razor strop container and supporting device have been embodied into a device which can be conveniently supported on a barber chair, or on a bracket attached to a wall or cabinet. For greater convenience, the strop handle is pivotally secured to the strop in order to lie adjacent the container when the strap is confined within the container.

In order to define the invention with greater particularity, reference is made to the accompanying drawings wherein:

Figure 1 is a side elevation of a barber chair on which the improved razor strop container and supporting device is attached;

Figure 2 is a front elevation of a portion of a barber's lavatory, mirrors and cabinets disclosing a convenient position of the improved container and supporting device attached thereto;

Figure 3 is a side longitudinal view in section of the improved container;

Figure 4 is a front longitudinal view in section of the improved container;

Figure 5 is a plan view of the improved razor strop container and supporting device disclosing the cam surfaces of the securing means;

Figure 6 is an enlarged view of the strop lower binding in engagement with the cam surfaces of the strop securing means;

Figure 7 is an enlarged side view in section of the container top with the strop withdrawn;

Figure 8 is an enlarged cross-sectional view taken on line 8—8 of Figure 4; and

Figure 9 is a view similar to Figure 8 showing a modification of the improved razor strop container.

The razor strop container 10 comprises a casting formed of side portions 11, an apertured and removable top 12 and a removable bottom 13. As shown in Figures 3, 4 and 7, the top 12 is formed with depending sides 14 which fit over

and frictionally engage the reduced sections of the upper part of the side portions 11. An elongated aperture 15 is provided in the upper surface of the top through which the strop is moved. On opposite sides of the aperture 15 a pair of oppositely turned cam flanges 16 are positioned. The pair of oppositely turned cam flanges are employed in releasably securing the strop in its withdrawn position as will be later described. The bottom 13 is also formed in the manner of a cap wherein the upturned sides 17 fit over and frictionally engage reduced sections of the side portions 11. The top 12 and bottom 13 are secured in place either by frictional engagement or by screws or other conventional locking means which are not shown.

The strop 20, which may be formed of laminae of leather and canvas or other materials, is shown positioned within the container in Figures 3 and 4 and shown in part withdrawn from the container in Figures 6 and 7. Bifurcated binding members 21 and 22 are located on each end of the strop. Securing means 23 in the form of nut-equipped bolts with reduced heads are shown although it is contemplated that other types of securing means such, for example, as rivets, etc., may be employed for attaching the binding members to the respective ends of the strop. Binding member 21 is formed with a depending section 24 having a reduced cross section and rounded edges 25 which engage the cam flanges 16 as shown in Figure 6 when the strop is withdrawn and rotated through a slight angle. Due to the curvature and inclination of the surfaces of cam flanges 16, the rounded edges 25 will readily pass thereover upon rotation as indicated in Figure 6 to secure releasably the strop in its withdrawn position. When it is desired to return the strop to its protected position within the container, the strop is rotated and the rounded edges pass over the cam surfaces in a manner to orient the binding member 21 with the aperture 15 so that the strop freely moves through the aperture. The lower portion of the depending section 24 is provided with a slot 26 through which passes the shank of an interconnecting link in the form of an eyebolt 27, the enlarged head 29 of which serves to maintain the eyebolt 27 fastened to the depending section 24 of binding member 21. Eyebolt 27 is connected to the loop of bolt 28 which in turn is secured to the central portion of the plunger 30. The connections between the binding member 21 and the plunger 30 provide a universal joint about which the strop may be freely moved. Figure 7 discloses the strop after removal from the container directed downwardly in parallel relationship adjacent the side of the container by virtue of the pivotal joints of the universal connection.

The weighted plunger 30 is formed to fit slidably the general contour of the interior of the container 10. Inasmuch as the plunger serves not only as a means for causing movement of the air and disinfecting gas in the circulatory system but also as a counterweight for the strop, the plunger is made sufficiently heavy to descend in the container and carry the strop with it when the strop is released from the cam flanges 16. Guide members 31 are provided within the container 10 which serve in the nature of tracks to guide the weighted plunger 30 during its movement within the container. In the embodiment shown in the drawings the guide members 31 are hollow, elongated elements and are positioned between the end walls of the container 10 and

the edges of the strop 20. The side sections of the plunger 30 are formed to engage slidably the guide members 31 as indicated by reference numerals 32, 33 and 34 of Figure 8 regardless of the cross sectional shape of the guide members. It is contemplated that various shaped guide members may be employed and the beveled members 31 shown in Figure 8 are illustrative of one type which has been found highly satisfactory in actual practice.

The guide members 31 also serve as passages for the gas circulating system of the present invention. As shown in Figures 3 and 4, the hollow guide members 31 terminate with open ends 35 in the top portion of the container and also terminate with open ends 36 in the lower portion of the container. The hollow guide members 31 are apertured at spaced intervals throughout their lengths as indicated by reference numeral 37. From the description of the improved strop container and supporting device thus far given it will be evident that upward movement of the plunger 30 from the position shown in Figures 3 and 4 will cause the gas in the upper portion of the container to be forced downwardly through the guide members 31 so that when the plunger reaches its upper position shown in Figure 7 substantially all of the gas within the container will have been circulated by the movement of the plunger.

An open topped container 40 is positioned in the bottom of the container 10 and if desirable it can be formed integral with the removal bottom 13. The disinfecting substance 41 is placed within the open topped container 40 from which it may freely pass into the gaseous phase and be circulated throughout the atmosphere of the container by the movement of the plunger 30. Many disinfecting substances are available for use in the improved container and supporting device and in general any disinfectant which will pass into the vapor state under normal conditions of temperature and pressure may be used. Aqueous solutions of formaldehyde have been found very effective in practice although oxygen, chlorine and ammonia liberating compounds can also be employed. The disinfecting substance can be placed in the open topped container 40 and be maintained in place by gravity or sponges or blotters impregnated with the disinfecting solution may be placed in the container in order to maintain the disinfectant from becoming displaced. As shown in Figures 3 and 4 the open topped container 40 is placed adjacent the lower open ends 36 of the guide members 31 and when the plunger 30 is moved upwardly, a portion of the air is caused to pass over the surface of the disinfecting substance which aids in the evaporation and diffusion of the disinfecting substance.

In order to maintain the disinfecting gas within the container, the aperture 15 is provided with a self closing washer 50 which is secured in place by a spring collar 51 adjacent the top of the container as best shown in Figure 7. The self-closing washer 50 which is formed of a resilient material such as rubber or felt contains a centrally positioned slit through which the strop and its appendages may pass with the exception of the plunger 30. In addition to sealing the container the washer 50 serves as a stop for the plunger 30 at the uppermost position of its travel as shown in Figure 7.

A stop 42 is positioned adjacent the bottom to serve as a rest for the plunger 30. The stop

is covered with a resilient material 43 such as rubber in order to eliminate noise when the plunger comes to rest.

Binding member 22 is provided with a pivotal connection 45 to which an intermediate link 46 is attached. On the end of the intermediate link opposite the pivotal connection 45, a second pivotal connection 47 is provided to which the binding member 48 of the strop handle 49 is attached. Use of the double pivotal connection at each end of the intermediate link 46 permits the strop handle 49 to hang adjacent the container 10 when the strop is in inoperative position as shown by Figure 3.

Figure 9 discloses a modification of the improved strop container and supporting device wherein tubular guide and duct members 60 are employed. In addition, the figure shows the manner in which the casing may be rounded such, for example, as at 61 in order to obtain a streamlined contour of the casing.

Figures 1 and 2 disclose positions wherein the strop container and supporting device have been used in practice. In Figure 1 the device 10 is mounted on the side of a barber chair 62 where it may be conveniently used by the barber. In Figure 2 the device 10 is attached to a cabinet 63 and spaced from the wall 64 to position it flush with the front edges of the cabinet. In each instance the device is attached by the use of brackets 65, the specific structure of which forms no part of this invention. In mounting the strop container and supporting device it is desirable to position it so that the strop handle 49 is within easy reach of the barber and so that the strap when withdrawn from the container is at the right height for sharpening purposes. It is also contemplated that the device may be mounted behind a vertical cabinet wall or the like in angular relationship so that the top 40 12 is flush with the vertical cabinet wall.

The operation and method of use of the strop container and supporting device is as follows: The strop handle 49 is grasped and the strop 20 is pulled upwardly until the rounded edges 25 of the binding member 21 are positioned adjacent the lower portion of the cam flanges as shown in Figure 6. Upward movement of the plunger 30 forces the gas within the container downwardly through the hollow guide members 31 causing a part of the gas to flow over the disinfectant substance. Rotation of the strop and the binding member 21 forces the rounded edges 25 to ride up onto the cam flanges 16 to secure releasably the strop in its withdrawn position. If desirable the strop can be further withdrawn until the loop of bolt 28 comes even with the top of the cam flanges in which position the strop may be suspended downwardly as shown in Figure 7 due to rotation of the shank of eyebolt 27 in slot 26. In this position plunger 30 is positioned adjacent the under side of the self-closing washer as shown in Figure 7. Upon releasing the strop either by moving it into vertical alignment with the aperture 15 from the position shown in Figure 7 or by rotating the rounded edges 25 so that they will slide down the cam flanges 16 and be directed into the aperture 15, the strop will be automatically returned within the container by virtue of the weight 30 to the position shown in Figures 3 and 4. Downward passage of the plunger causes the gas within the container to be forced upwardly through the guide members 31. In both directions of movement the gas is free to pass into 75

and from the hollow guide members 31 through the apertures 37 and the open ends 35 and 36. The forced circulation of the air and disinfecting gas causes complete diffusion throughout the interior of the container and the self-closing washer 50 maintains the gases within the container without loss due to leakage.

Various modifications and embodiments such, for example, as placement of the air ducts outside of the container and forming the plunger to slidably engage the container walls will be apparent to those skilled in the art, and it is my desire that the appended claims shall cover all modifications and arrangements which come within the scope and spirit of my invention.

Having thus described certain embodiments of the invention, what is claimed as new and desired to secure by Letters Patent is:

1. A razor strop container and supporting device comprising a casing having gas confined therein, a movable plunger slidably positioned within said device, plunger moving means comprising a razor strop having one end connected to said plunger and passage means between the upper and lower parts of the casing through which the gas confined within the casing may flow from one side of the plunger to the other during movement of the plunger by the moving means.

2. A razor strop container and supporting device comprising a casing having a gas confined therein, a cover for said casing provided with an opening therein, a razor strop slidably positioned in said casing and adapted to pass through said opening, means for sealing said opening adjacent said strop and circulating means for said confined gas comprising a movable plunger secured to said strop and passage means for the gas extending from one side to the other side of said plunger.

3. A container for a razor strop having an aperture through which the strop may pass, means for confining a gas within said container, a razor strop slidably positioned within said container, hollow guide members secured adjacent opposite walls of the container, and a movable plunger connected to said strop and in slidable engagement with said guide members.

4. A razor strop container and supporting device comprising a casing, a razor strop slidably positioned within said casing, a cover for said casing provided with an opening through which said strop may be withdrawn, sealing means comprising a washer adjacent said opening for confining a gas within said casing, means comprising a weighted plunger for returning said strop within said casing from its withdrawn position, said latter means cooperating with passage means extending between the upper and lower positions of said casing to circulate the gas within the casing during movement of the strop.

5. A razor strop container and supporting device comprising a casing, a razor strop slidably positioned within said casing, a cover for said casing provided with an opening through which said strop may be withdrawn, sealing means comprising a washer adjacent said opening for confining a gas within said casing, a source of disinfecting gas within said casing, means comprising a weighted plunger for returning said strop within said casing from its withdrawn position, said plunger cooperating with a plurality of apertured passages extending between the upper and lower portions of said casing to circulate the dis-

infecting gas within the casing during movement of the strop.

6. A razor strop container and supporting device comprising a casing, a razor strop slidably positioned within said casing, a cover for said casing provided with an opening through which said strop may be withdrawn, sealing means comprising a washer adjacent said opening for confining a gas within said casing, a slideable plunger within said casing connected to the lower end of said strop and movable therewith, means for guiding said plunger comprising elongated hollow passage members positioned adjacent opposite walls and a stop member positioned in the lower part of said casing against which the plunger rests when the strop is positioned within the container.

7. A razor strop container and supporting device comprising a casing, a razor strop slidably positioned within said casing, a cover for said casing provided with an opening through which said strop may be withdrawn, a means for returning the strop within the casing from its withdrawn position, a binding member having

curved edges on its lowermost portion secured to the lower end of said strop, oppositely turned latching flanges having curved surfaces adapted to guide said binding member therebetween located on opposite exterior sides of the opening in the cover whereby the strop is releasably secured in its withdrawn position by rotation of the strop after withdrawal from the casing.

8. A razor strop container and supporting device comprising a casing, a razor strop slidably positioned within said casing, a handle for said strop, a binding member secured to the upper end of said strop, a cover for said casing provided with an opening through which said strop may be withdrawn, means for returning said strop within the container from its withdrawn position, an intermediate link having one end hingedly secured to said binding member and the other end hingedly secured to said strop handle, said intermediate link being of such length to permit the handle to rest adjacent the casing side when the strop is positioned within the container.

JOHN E. GILLESPIE.
